OWL COIN BANK OR SIMILAR CONTAINER

Joseph B. Stier, New York, N. Y.

Application February 2, 1950, Serial No. 7,659

Term of patent 7 years

(Cl. D34—11)

To all whom it may concern:

Be it known that I, Joseph B. Stier, a citizen of the United States, residing in New York city, county and State of New York, have invented a new, original, and ornamental Design for Owl Coin Bank or Similar Container, of which the following is a specification, reference being had to the accompanying drawing, forming a part thereof, in which:

Fig. 1 is a front view of an owl coin bank or similar container, showing my new design;

Fig. 2 is a side elevational view thereof, and
Fig. 3 is a rear elevational view thereof.

I claim:

The new ornamental design for an owl coin bank or similar container, as shown.
JOSEPH B. STIER.
